METHOD OF REMOVING SULPHUR IMPURITIES FROM PETROLEUM OILS

William Alvah Smith, Hamburg, N. Y.

No Drawing. Application February 27, 1930,
Serial No. 431,990

6 Claims. (Cl. 196—30)

This invention relates to the removal of impurities, such as sulphur, whether in a combined or uncombined condition, from impure hydrocarbon compounds and mixtures thereof. Heretofore, it has been common practice to partially remove undesirable impurities, such as sulphur compounds, from hydrocarbon compounds and mixtures thereof, some of which may be unsaturated, by various treating agents, such as the mineral acids, and of which sulphuric acid is the most commonly used, or anhydrous metallic halides, such as aluminum chloride, as described in my co-pending patent application Serial No. 393,586, filed September 18, 1929.

In the treatment of certain hydrocarbon mixtures, such, for example, as petroleum compounds and particularly the distillates from petroleum cracking stills, it has been found that the unsaturated hydrocarbons in those mixtures or distillates, that is, hydrocarbons containing less than the maximum amount of hydrogen which could be included in the combination, are, to a considerable extent, polymerized into undesirable or saturated hydrocarbon compounds by the sulphur removal agents heretofore employed. Such undesirable or saturated compounds when burned in an internal combustion engine are more likely to "knock" or detonate than are the unsaturated compounds before polymerization.

Frequently these polymerized or saturated hydrocarbons have a higher boiling or vaporizing point than is desirable in an internal combustion engine fuel, and therefore are sometimes removed from the desulphurized mixture and discarded, which decreases the yield of marketable fuel obtained from a given quantity of untreated hydrocarbon compounds. The polymerization of unsaturated compounds into saturated compounds is also frequently undesirable where the compounds are to be used in chemical reactions. For example, the unsaturated compounds are chlorinated more easily than are saturated compounds.

I have discovered that polymerization of the unsaturated compounds into saturated compounds can be largely prevented or minimized, the sulphur removal action greatly accelerated, and the percentage of impurities removed greatly increased, if the removal action is carried on in the presence of an accelerating or inhibiting agent or substance. By reason of this, a more desirable product is obtained, and the sulphur removal processes may be performed at temperatures not heretofore feasible or desirable.

Various organic compounds have been found suit-

able as the accelerating or inhibiting agent, and may be used in the usual methods of removing sulphur from hydrocarbon compounds.

The selection of the agent depends somewhat upon the exact nature of the impurities to be removed, the degrees of unsaturation of the hydrocarbon compounds from which the impurities are to be removed, the amount of impurities to be removed, and the conditions under which the removal is to be performed. In general, I have found that anhydrous treating agents yield better results than those in which water dilution occurs, and when sulphuric acid is used, I have found that in the presence of an inhibiting agent, a concentrated sulphuric acid as near as possible to a one hundred percent pure acid yields more satisfactory results than does commercial oil of vitriol acid, which is usually about ninety-five percent strength.

The amount of the inhibiting agent which it is desirable to use, while varying somewhat with the material to be treated, the impurities to be removed, and the character of the sulphur removal agent, is in general less than the molal quantity of the sulphur removal agent employed.

Among the various inhibiting agents which may be satisfactorily employed, may be mentioned furfural which is a cyclic aldehyde and nitro-benzene. The hydrocarbons are treated with the sulphur removal agent, such as sulphuric acid, in the presence of the inhibiting agent, such as furfural or nitro-benzene. The inhibiting agent may be added to the sulphur removal agent, such as sulphuric acid, before the latter is added to the hydrocarbon mixtures or to the hydrocarbon mixture before the sulphur removal agent is added to the hydrocarbon mixture. I prefer to add the inhibiting agent to the hydrocarbon mixture first and then to add the sulphur removal agent to this combined mixture.

After the hydrocarbon compounds or mixtures thereof have been treated with the sulphur removal agent and the inhibiting agent, the complete mixture may be agitated continuously until the reaction is complete. The reaction I have found is usually completed within about ten minutes when the acid treatment is used for the removal of sulphur. After the reaction is complete, the combined mixture is left quiescent, whereupon the residue separates out carrying the impurities and the treating agent, which then may be removed in any suitable manner such as by draining off the supernatant liquid, or by treatment with fuller's earth or other adsorbent material, or by washing with water. This treated

material may then be subjected to any further neutralization or treatment as desired to finish it for the market. The residue may be then disposed of as usual in the industry, or treated for the recovery of any valuable components thereof.

Without the use of the inhibiting agent or material, the acidic sulphur removal treatment often required several hours or days in order to get a high percentage of removal of the impurities.

10 The use of the inhibiting agent also speeds up the reaction and makes the removal of impurities more complete, without undesirable polymerization, of the hydrocarbons. I have found that by the use of the inhibiting agent, the action 15 is more rapid at the same temperatures, and one may use higher temperatures during the removal reaction in order to speed up the reaction without materially increasing the polymerization of the unsaturated compounds, which polymerization always heretofore occurred to a very great extent whenever the sulphur removal reaction was speeded up by the use of the higher temperatures.

Removal of impurities with such an inhibiting 25 agent may be applied to hydrocarbon mixtures in any stage of refinement or in crude form, and produces a product which I have found will stand exposure to light more satisfactorily than products obtained by similar removal processes without the use of the inhibitor. The removal of 30 sulphur, when in the presence of the inhibitor, is more complete for a given amount of the sulphur removing agent than is possible without the use of an inhibitor, and the inhibitor may be used without any change in the apparatus used heretofore for sulphur removal.

35 I claim:

1. The method of removing sulphur impurities from petroleum distillates and oils, which comprises first adding thereto in liquid phase a relatively small quantity of furfural, and then treating that mixture with concentrated sulphuric acid in an amount sufficient to remove or render inert the sulphur content of said distillates while inhibiting the polymerization of unsaturated 40 components of said distillates.

45 2. The method of removing sulphur impurities

from petroleum distillates and oils which comprises concomitantly treating said distillates with furfural and with concentrated sulphuric acid in an amount sufficient to remove or render inert the sulphur content of said distillates while inhibiting the polymerization of unsaturated components of said distillates.

5 3. The method of removing sulphur impurities from petroleum products, which comprises reacting upon the impurities of such products with furfural and an acidic sulphur removal agent selected from the group consisting of sulphuric acid and aluminum chloride and in quantities sufficient to remove or render inert the sulphur content of said products, while inhibiting the polymerization of unsaturated components of such products.

10 4. The method of removing sulphur impurities from petroleum products, which comprises reacting upon said products at the same time with furfural and with a concentrated mineral acid, in amounts sufficient to remove or render inert the sulphur content of said products while inhibiting the polymerization of unsaturated components of said products, the amount of furfural being, in 15 general, less than approximately the molal quantity of the sulphuric acid employed.

15 5. The method of removing sulphur impurities from petroleum products, which comprises first mixing furfural with said products and then adding to said mixture an acidic sulphur removal agent selected from the group consisting of sulphuric acid and aluminum chloride, and in quantities sufficient to remove or render inert the sulphur content of said products, while inhibiting the polymerization of unsaturated components of said products.

20 6. The method of removing sulphur impurities from petroleum products which comprises reacting upon said products at the same time with a mineral acid and furfural in amounts sufficient to remove or render inert a substantial proportion of the sulphur content of said products while inhibiting the polymerization of unsaturated components of said products.

25 30 35 40 45 WILLIAM ALVAH SMITH.
